UNITED STATES PATENT OFFICE.

JAMES O. STEENSLAND, OF BLANCHARDVILLE, WISCONSIN.

TEMPERATURE-REGULATOR.

1,153,407.

Specification of Letters Patent. Patented Sept. 14, 1915.

Application filed December 8, 1914. Serial No. 876,166.

To all whom it may concern:

Be it known that I, JAMES O. STEENSLAND, a citizen of the United States, residing at Blanchardville, in the county of Lafayette and State of Wisconsin, have invented a new and useful Temperature-Regulator, of which the following is a specification.

The device forming the subject matter of this application is a temperature operated means for draining a radiator or like structure, when the temperature falls, to the end that the radiator may not be broken due to a freezing of its contents.

The present invention aims primarily to provide a novel form of temperature actuated means for holding the valve against rotation.

Another object of the invention is to provide novel means for rotating and controlling the action of the valve.

It is within the scope of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawing: Figure 1 shows the invention in vertical longitudinal section; Fig. 2 is a bottom plan, the valve having been shifted through an arc of 90°; Fig. 3 is a section on the line 3—3 of Fig. 1; Fig. 4 is an elevation of the valve; Fig. 5 is a fragmental side elevation showing a portion of the casing and depicting particularly, the valve holding lug thereon, parts being shown in section.

In carrying out the invention there is provided a casing, the same comprising a body 1 of circular contour, open at its inner end, the outer end of the body 1 being closed by a front plate 2 having a projecting boss 3. The inner end of the body is provided with a circumscribing rib 100 against which abuts a diaphragm 101, the diaphragm being yieldable and being adjusted by a screw 102 threaded into a bridge 103 extended across the casing. In the interior of the body 1 there is a reservoir 4. Extended

longitudinally of the body 1 adjacent its bottom is a cylindrical passage 5, opening into the reservoir 4 as shown at 6. Across the forward end of the passage 5 extends a wall 7. The boss 3 is provided with a bore 8. An inlet opening 10 establishes a communication with the interior of the passage 5. The body 1 is threaded as shown at 11 adjacent the front plate 2 for union with a radiator, and in this connection it is to be understood that the word "radiator" is to be construed to mean any structure wherewith a device of this type may be assembled profitably. In the wall 7 there is a port 12, the wall 7 being provided with an opening 14.

Located within the passage 5 is a longitudinally expansible and contractible element 15 preferably in the form of a light metal tube, although it is not obligatory that metal be employed. The forward end of the tube 15 is closed and the rear end of the tube is open, the rear end of the tube being secured circumferentially as shown at 16 to the wall of the passage 5. The tube 15 preferably is corrugated as shown in the drawings. In the bottom of the casing is threaded a closure plug 17 which may be sealed as shown at 17a. At its forward end, the expansible tube 15 is supplied with a finger 18 which passes through the opening 14 in the wall 7 and enters the bore 8 in the boss 3.

Journaled for rotation in the bore 8 of the boss 3 is a valve 19. The valve 19 is provided with a passage 20 terminating in a lateral extension 21. The lateral extension 21 at times may be lined up with the port 12 in the wall 7. Upon its upper end, the valve 19 is provided with an eccentric lug 22 having a flat side. The extremity of the finger 18 on the tube 15 lies against the flat side of the lug 22 and holds the valve 19 against rotating. When the valve is thus held, the extension 21 of the outlet passage 20 in the valve 19 is out of alignment with the port 12 in the wall 7.

Adjacent its lower end, the valve 19 is reduced in diameter to form a shoulder 23. A flange 24 is fashioned on the lower end 105 of the boss 3, the flange coöperating with the shoulder to hold the valve 19 in place in the bore 8. Surrounding the reduced lower end of the valve 19 is a coiled spring 25, one end of which is secured as shown at 26 to the boss 3, the other end of which is secured to the valve. The spring 25 constitutes a

means for rotating the valve 19 when the finger 18 on the tube 15 is retracted out of engagement with the lug or shoulder 22 on the valve.

5 At its lower end, the valve 19 may be bifurcated to form ears 27. Extended through the ears 27 is a pivot element 28, one end of which is fashioned in a finger 29 adapted to operate with the lug 30 on the lug 3. When the valve 19 is rotated by means of the spring 25 the finger 29 coacts with the lug 30 to prevent further rotation of the valve, the extension 21 of the outlet passage in the valve under such circumstances being lined up with the port 12 in the wall 7. Pivotally supported on the element 28 is a latch 32. The latch 32 is frictionally held between the ears 27 so that it will stand in any position to which it has been swung manually. In the lower end of the lug 3 there is formed a notch 31. The valve 19 may be rotated by hand through the medium of the latch 32, and then the latch 32 may be turned up to engage in the notch 31, under which circumstances, the valve will be held against rotation.

In practical operation, the reservoir 4 and the tube 15 are filled with a liquid which freezes at a temperature which is low 30 compared with the freezing point of water. The liquid within the reservoir 4 and the tube 15 may be inserted by removing the plug 17, after which the plug is sealed as at 17^a. By manipulating the screw 102 a 35 proper pressure may be created within the reservoir 4 and the tube 15 by the movement of the diaphragm 101. The extension 21 of the passage 20 in the valve 19 is disposed out of alignment with the port 12 in the wall 7 and the finger 18 on the tube 15 lies against the flat side of the lug 22 on the valve 19 to hold the valve against rotating by the action of the spring 25. The liquid within the radiator or other structure where- 40 45 with the casing is assembled is adapted to pass through the casing by way of the inlet 10, the interior of the passage 5, the port 12, the extension passage 21 in the valve 19 and the passage proper 20 in the valve, but when the parts are arranged as above described, the port 12 is closed by the valve.

When the body of liquid within the reservoir 4 and the tube 15 cools, the tube 15 contracts. By this operation, the finger 18 55 on the end of the tube 15 is retracted out of engagement with the lug 22 on the valve 19 and the valve 19 is rotated by the action of the spring 25. The extension 21 of the passage 20 in the valve 19 is thus lined up 60 with the port 12 and a communication is established through which the water within the radiator may drain, the finger 29 coöperating with the lug 30 in the manner hereinbefore described. If desired, the latch 65 32 may be swung upwardly on the pivot ele-

ment 29 and be brought into registration with the notch 31 thus to hold the valve 19 positively against rotation.

Having thus described the invention, what is claimed is:—

1. In a device of the class described, a casing comprising a chamber and having a passage terminating in a port; a valve journaled in the casing and having a shoulder; the valve having an outlet adapted to communicate with the port when the valve is rotated to a predetermined position; yieldable means for rotating the valve; a tubular, contractible element carried by the casing and communicating with the chamber; and a finger on the contractible element, the finger coöperating with the shoulder to prevent rotation of the valve and to maintain the outlet in the valve out of communication with the passage in the casing. 70 75 80

2. In a device of the class described, a casing comprising a chamber and having a passage terminating in a port; a valve journaled in the casing and having a shoulder, the valve having an outlet adapted to communicate with the port when the valve is rotated to a predetermined position; yieldable means for rotating the valve; a tubular, contractible element carried by the casing and communicating with the chamber; a finger carried by the contractible element, the finger coöperating with the shoulder to prevent a rotation of the valve and to maintain the outlet in the valve out of communication with the port; and latch mechanism 90 95 100 coöperating with the casing and the valve to hold the valve against rotation.

3. In a device of the class described, a casing comprising a chamber and having a passage terminating in a port; a valve journaled in the casing and having a shoulder, the valve having an outlet adapted to communicate with the port when the valve is rotated to a predetermined position; means for rotating the valve; a tubular contractible element carried by the casing and communicating with the chamber; a finger mounted on the contractible element, the finger coöperating with the shoulder to prevent a rotation of the valve and to maintain the outlet in the valve out of communication with the passage; and interengaging elements on the valve and the casing for limiting the rotation of the valve, thereby to align the outlet in the valve with the passage in the casing. 105 110 115

4. In a device of the class described, a casing comprising a chamber having an outlet; a valve controlling the outlet; a hollow contractible member communicating with the chamber, the chamber being provided with an opening exposing the contractible member; interengaging elements on the contractible member and the valve; a yieldable diaphragm constituting a closure for the 120 125 130 135 140

chamber; and means for adjusting the diaphragm.

5. In a device of the class described, a casing comprising a chamber and having a passage terminating in a port; a valve journaled in the casing and having a shoulder; the valve having an outlet adapted to communicate with the port when the valve is rotated to a predetermined position; yieldable means for rotating the valve; a tubular, contractible element carried by the casing and communicating with the chamber; a finger on the contractible element, the finger coöperating with the shoulder to prevent a rotation of the valve and to main-

tain the outlet in the valve out of communication with the passage in the casing; a latch pivoted to the valve; and means on the casing for engaging the latch, the latch constituting means whereby the valve may be rotated manually when the latch is out of engagement with the said means. 20

In testimony that I claim the foregoing as my own, I have hereto affixed my signature in the presence of two witnesses.

JAMES O. STEENSLAND.
